UNITED STATES PATENT OFFICE

WILLIAM L. RANSON, OF TAKOMA PARK, MARYLAND, ASSIGNOR TO GRAHAM-WHITE SANDER CORPORATION, OF ROANOKE, VIRGINIA, A CORPORATION OF VIRGINIA

VALVE FOR LOCOMOTIVE SANDERS

Application filed July 2, 1930. Serial No. 465,407.

The invention relates to means for applying sand to the rail beneath the traction wheels of locomotives or the like.

In Patent No. 1,263,722 granted to William H. White on April 23rd, 1918, there is disclosed a locomotive sanding device embodying a sand box or dome from which lead sand pipes connected with sand traps having discharge pipes leading therefrom to points 10 in advance of the driving wheels of the locomotive. The sand is forced out by compressed air controlled by a suitable valve means within the locomotive cab. In this particular device and in others of a more or 15 less similar nature, the sand trap has therein a nozzle from which compressed air discharges for forcing the sand through the delivery pipes. These devices also include cleaning means generally consisting of a port 20 located opposite the entrance to the delivery pipe and receiving compressed air from a separate pipe, the purpose being to prevent clogging of the delivery pipe. In devices of this nature it is customary to provide a valve for 25 controlling the flow of compressed air successively to the cleaning pipe and discharge jet, the valve being manually operable to control the flow of pressure.

The present invention has for its principal 30 object the provision of a valve interposed between the engineer's control valve and the sanding and cleaning means, the valve being so constructed and arranged as to permit the passage of compressed air for a short period of time to the cleaning port and then 35 automatically closing so that the air will be supplied to the sanding jet only.

An important object of the invention is to 40 provide a valve of this character which requires no manual control whatsoever but which operates entirely by compressed air whenever the manual valve in the cab is opened.

Another object of the invention is to provide 45 in a sanding device a valve of this type which will remain open for a predetermined period to insure the proper flow of compressed air to the cleaning pipe or port and which will then close by the building up of 50 air pressure within it to cut off the supply

of air to the cleaning port and direct it entirely to the sanding mechanism.

Another object of the invention is to provide a valve of this type which will return automatically to normal position when the compressed air supply is cut off by means of the control valve in the cab, so as to be ready for subsequent operation whenever necessary. 55

An additional object of the invention is to provide a valve of this character which will be simple and inexpensive to manufacture, easy to install, positive and automatic in action, efficient and durable in service, and a general improvement in the art. 60

To the attainment of the foregoing and 65 other objects and advantages, the invention preferably consists in the details of construction and the arrangement and combination of parts to be hereinafter more fully described and claimed, and illustrated in the 70 accompanying drawing in which:

Figure 1 is a fragmentary side elevation of a locomotive equipped with a sanding mechanism embodying my novel valve, and

Figure 2 is a vertical longitudinal section 75 through the valve alone showing the movable part thereof at one limit of its movement.

Referring more particularly to the drawing, the numeral 1 designates, generally, a portion of a locomotive having the usual 80 driving wheels 2. The numeral 3 designates a sand box or dome which is mounted on top of the boiler as is customary and which contains sand conducted through the sand pipes 4 to sand traps 5 and 6 from which lead delivery pipes 7 and 8, the former being provided for the purpose of conducting or delivering sand in advance of the driving 85 wheels and the latter being for the purpose of conducting sand to the rear thereof when the locomotive is operated in reverse. The sand traps, sand pipes and delivery pipes are provided at both sides of the locomotive as will of course be readily understood and it is naturally intended that the action will be 90 the same at both sides whether the locomotive be running forwardly or rearwardly. In view of the disclosure in Patent No. 1,263,722 granted April 23rd, 1918, to William H. White it is thought unnecessary to illustrate 100

the construction of the sand traps as a full understanding in regard thereto may be had by inspecting said patent. It is thought sufficient for present purposes to state that compressed air is supplied to the discharge jets 5 within the traps 5 and 6 through pipes 9 and 10 respectively, and that compressed air is supplied to the cleaning ports through pipes 11 and 12 respectively. The discharge pipes 9 and 10 at each side of the locomotive 10 are connected by transverse pipes 13 and the cleaning pipes 11 and 12 at each side are similarly connected by pipes 14. As mentioned above, the usual practice is to provide manually operated valve means for controlling flow of compressed air to the pipes 11 or 12, and 9 or 10, successively, this depending upon the direction of movement of the locomotive. The objection to manual means 15 of this type, such as disclosed in the above mentioned White Patent No. 1,263,722, is that the engineer may permit compressed air to pass to the cleaning pipes and ports for either too long or too short a time. If the time is too short the delivery pipes may not 20 be properly unclogged and if the time is too long there is a waste of compressed air. As a matter of fact I have not shown any manual valves for controlling the passage of compressed air to the sanding devices as this is 25 a detail immaterial in the present combination.

In accordance with the invention I provide 30 automatic valves indicated generally at 15 and 16 connected with supply pipes 17 and 18 which extend to the cab and which are 35 equipped therewith with any suitable control valves, not shown. The valve 15 has connected therewith the pipes 9 and 11 which lead to the forward sand trap 5, while the valve 40 16 has connected therewith the pipes 10 and 12 which connect with or lead to the rear sand trap 6. As the valves 15 and 16 are 45 identical in construction a description of one will suffice.

Each of the valves 15 and 16 is shown as 50 comprising a body 19 preferably of general cylindrical shape and formed to provide a relatively large chamber 20 and a relatively small chamber 21, the outer ends of the 55 respective chambers being normally closed by caps 22 and 23 here represented as screwed in place though it is to be understood that they may be fastened in any desired manner as this is an immaterial detail. At one side, the body 19 is provided with a boss 24 within 60 which is a port 25 communicating with the chamber 20, and the pipe 17 or 18 as the case may be is screwed into this boss. At the opposite side the body is formed with two 65 bosses 26 and 27 within which are ports 28 and 29 leading into the chamber 20. The pipes 9 and 11, or 10 and 12 as the case may be, are screwed into these bosses 26 and 27 respectively. The chamber 20 of course com-

municates through the ports 25, 28 and 29 with the pipes 17, 9 and 11, or 18, 10 and 12, as the case may be, at certain periods in the operation, while the chamber 21 is open to the atmosphere through a bleed port 30.

Slidably mounted within the body 19 is a piston indicated as a whole by the numeral 31 and comprising differential heads 31 and 32 located within the respective chambers 20 and 21. Any desired packing means, either 70 spring or yieldable, may be provided for the heads, such details being merely mechanical and constituting no important part of the invention. The heads 31 and 32 are connected by a reduced stem 33 and may be provided 75 at their outer faces or sides with projections 34 and 35 adapted to engage against abutments 36 and 37 on the inner faces of the caps 22 and 23 respectively when the entire piston reaches the ends of its movements. 80 The piston is normally urged in one direction, that is to say into its normal position as by means of a spring 38 preferably of the conical type so as to occupy the minimum space when compressed. The piston head 31 is formed 85 with a bleed port 39 which extends therethrough and which consequently permits passage of air from above to below this head for a reason which will become apparent.

The valve 15 is installed connected between 90 the pipe 17 and the pipes 9 and 11, while the valve 16 is installed between the pipe 18 and the pipes 10 and 12. Normally, that is to say when there is no sanding of the rails 95 needed the piston in the valve is at the lowermost position as shown in Figure 2 of the drawing. Whenever it is desired to feed sand on to the track in advance of the driving 100 wheels 2, the engineer opens whatever control pipe is provided in the pipe 17 whereupon compressed air flows through the pipe 17 into the valve 15, the air entering the chamber 20 and passing out through the pipes 9 and 11. However, a certain amount of air will 105 pass through the port 39 in the head 31 and build up pressure beneath this head. This is possible owing to the difference in the 110 diameters of the heads 31 and 32. When the air pressure beneath the piston head 31 builds up, as it will very shortly, the pressure 115 against the underside of the head 32 will cause the piston as a whole to move upwardly, the head 31 then riding over and closing the port 29 which communicates with the pipe 11 leading to the cleaning port. The air entering 120 the chamber 20 then passes out only through the port 28 and pipe 9 to the sand trap 5 where sand is ejected into and through the pipe 7 in advance of the forward driver. Of course it should be understood that the sanding mechanism is the same at both sides of 125 the locomotive and will operate simultaneously at both sides owing to the provision of the transverse pipes 13 and 14. As the piston rises air in advance of the head 32 escapes 130

through the bleed port 30 so that there will be no pressure built up in advance of the head 32. Of course the spring 38 becomes compressed but as it may be a very little spring it will not in any way seriously oppose movement of the piston. When the sanding is completed the operator of course cuts off his control valve in the pipe line 17 and as the pressure within the chamber 20 reduces by virtue of the escape of the air through the port 28 the spring 38 will expand and force the piston down to its original or normal position.

In case the locomotive is backed and it is desired to apply sand to the rails behind the rear drivers 2, the control valve in the pipe 18 is opened to actuate the valve 16 in exactly the same manner as above described so that sand will be ejected through the sand pipes 8 at the opposite sides of the locomotive.

From the foregoing description and a study of the drawing it will be apparent that I have thus provided a very simple valve device which will operate automatically to permit flow of compressed air through the cleaning pipes and ports of the sand traps and then cut off the cleaning blast so that air will be supplied only to the sanding mechanism. A distinct advantage of this is that it will be impossible for the engineer, through carelessness or any other reason, to waste compressed air by permitting it to pass for an excessive length of time through the cleaning ports. A short sharp blast through the cleaning pipe and port should be sufficient and consequently it is of particular advantage to provide an automatic means for accomplishing this so that the major portion of the air may be utilized for sanding. Another feature of advantage is that after actuation of the sanding mechanism, that is to say after the engineer closes the valve in the supply line the automatic valve will return to its normal or initial position, already for repeated action when necessary. The invention is marked by extreme simplicity especially as there is but one moving part. Furthermore, lubrication is a simple matter as any necessary oil may be readily injected through the bleed port in the top cap. There should be no great degree of wear and as a consequence the mechanism should have a remarkably long life. It is believed from the foregoing that the construction, operation and advantages should be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such

changes constitute no departure from the spirit of the invention or the scope of the claims hereunto appended.

Having thus described the invention, I claim:

1. In a locomotive sanding apparatus including a sand dome, sand traps receiving sand from the dome and having delivery pipes connected therewith, each sand trap having a cleaning pipe leading thereinto and having a sand discharge pipe leading thereto, a compressed air supply pipe, and an automatic valve interposed between the supply pipe and the cleaning pipe and discharge pipe, said automatic valve being normally open whereby upon the admission thereto of compressed air from the air supply pipe the air will initially pass into the cleaning pipe and discharge pipe, and said valve being adapted to close partially under the influence of air pressure for entirely cutting off flow of compressed air to the cleaning pipe while permitting flow to the discharge pipe.

2. In a locomotive sanding mechanism, the combination of a sand dome, a sand trap receiving sand therefrom, a sand delivery pipe leading from the sand trap, a cleaning pipe connected with the sand trap, a compressed air supply pipe, and a normally open valve interposed between the supply pipe and the cleaning and discharge pipes, said valve being operated by pressure of compressed air passing therethrough for entirely cutting off communication between the supply pipe and the cleaning pipe while communication with the discharge pipe is maintained.

3. In a locomotive sanding mechanism, the combination of a sand dome, a sand trap receiving sand therefrom, a sand delivery pipe leading from the sand trap, a cleaning pipe connected with the sand trap, a compressed air supply pipe, and a fluid pressure operated valve interposed between the supply pipe and the cleaning and discharge pipes, said valve being normally open to permit initial flow of compressed air from the supply pipe to the cleaning and discharge pipes and being movable upon building up of air pressure within itself to cut off communication to the cleaning pipe entirely while maintaining established communication with the discharge pipe.

4. In a locomotive sanding mechanism, the combination of a sand dome, a sand trap receiving sand therefrom, a sand delivery pipe leading from the sand trap, a cleaning pipe connected with the sand trap, a compressed air supply pipe, and a fluid pressure operated valve interposed between the supply pipe and the cleaning and discharge pipes, said valve being normally open to permit initial flow of compressed air from the supply pipe to the cleaning and discharge pipes and being movable upon building up of air pressure within itself to cut off communication to the clean-

ing pipe while maintaining established communication with the discharge pipe, said valve including a movable piston having differential heads with the larger head provided with means for passage of air therethrough.

5 5. In a locomotive sanding mechanism, the combination of a sand dome, a sand trap receiving sand therefrom, a sand delivery pipe leading from the sand trap, a cleaning pipe connected with the sand trap, a discharge pipe connected with the sand trap, a compressed air supply pipe, and a normally open valve interposed between the supply pipe and the cleaning pipe and discharge pipe, said valve initially effecting communication between the supply pipe and the cleaning and discharge pipes, and means within the valve for effecting movement thereof under the development therein of differential air pressures for cutting off communication to the cleaning pipe while maintaining it with the discharge pipe.

10 6. In a locomotive sanding mechanism including a sand trap having a delivery pipe, a cleaning pipe and a discharge pipe connected therewith, the combination of a single supply pipe, means interposed between the supply pipe and the cleaning and discharge pipes for initially supplying compressed air from the supply pipe to the cleaning and discharge pipes, and automatically acting differential fluid pressure operated means for cutting off communication to the cleaning pipe while maintaining it with the discharge pipe.

15 7. In a mechanism of the character described, a control valve comprising a body having an inlet and a pair of spaced outlets, a piston slidable within the body and having differential heads normally in non-obstructing relation to the outlets, the larger head having a port therethrough permitting passage of fluid pressure to build up beneath the same for moving the piston into position 20 with the larger head closing one outlet.

25 8. In a mechanism of the character described, a control valve device comprising a body formed with chambers of different diameters and provided with an inlet and spaced outlets all communicating with the larger chamber, a piston slidable axially within the body and having differential heads located within the respective chambers, the larger head having a port therethrough permitting passage of air for equalizing the pressure at both sides of the larger head whereby the pressure acting against the smaller head may move the piston longitudinally to cut off communication through one outlet while 30 permitting communication to the other.

35 9. In a locomotive sanding mechanism including a sand trap having a delivery pipe, a cleaning pipe and a discharge pipe connected therewith, the combination of a fluid pressure supply pipe, and means interposed

40 and normally establishing communication between the supply pipe and the cleaning and discharge pipes for initially supplying fluid pressure from the supply pipe to the cleaning and discharge pipes, said means embodying differential pistons movable on the building up of air pressure to cut off communication to the cleaning pipe while maintaining communication with the discharge pipe.

45 10. In a locomotive sanding mechanism including a sand trap having a delivery pipe, a cleaning pipe and a discharge pipe connected therewith, the combination of a supply pipe and normally open valve means interposed between the supply pipe and the cleaning and discharge pipes for initially supplying compressed air from the supply pipe to both the cleaning and discharge pipes, said valve means embodying a slidable piston having differential heads and normally non-obstructing relation to the cleaning and discharge pipes, and means for effecting an overbalancing of the pressure against the smaller head so that the piston 50 may move into a position with the larger head cutting off communication to the cleaning pipe.

55 11. In a mechanism of the character described, a control valve comprising a body having an inlet and a pair of spaced outlets, a piston slidable within the body and having differential heads normally in non-obstructing relation to both outlets, and means for bypassing fluid pressure to a point beneath the larger head whereby fluid pressure may build up beneath the latter for moving the piston into position with the larger head closing one outlet.

60 12. In a sanding mechanism including a fluid supply conduit, a discharge conduit and a cleaning conduit, means normally establishing communication between the supply conduit and both the discharge and cleaning conduits and operable upon flow of fluid pressure from said supply conduit to cut off communication between the supply conduit and the cleaning conduit while maintaining communication between the supply conduit and said discharge conduit.

65 In testimony whereof I affix my signature.
WILLIAM L. RANSON.
